PRINTING TYPE

Solomon Siegelbaum, New York, N. Y.

Application October 14, 1938, Serial No. 234,986

7 Claims. (Cl. 101—398)

This invention relates to improvements in printing type, and particularly to improvements in single types such as Monotype and foundry type.

One of the objections to the use of single types such as Monotype and foundry type is that the spaces work up and contact the inking surface in the type inking operation and then contact the paper in the printing operation, with the result of faulty printing and an unsatisfactory appearance of the printed sheet. This objection and others inherent in the use of single types are entirely overcome by this invention.

The invention has for its main object the provision of type and lead adapted to be interlocked to prevent workups and pull-outs on the press and also to prevent type and spaces from dropping out when the form is lifted.

Another object of the invention is to provide type and leads which will be so interlocked that an entire set line may be handled as a unit, making the handling of movable type more convenient.

Another object of the invention is to provide interlocking type and leads of such form that the type may be set directly against the lead of the preceding line and the lines of type may be set solid without removing the leads from the lines.

There are other objects and advantages of the invention which will appear hereinafter.

It will be understood that this improvement applies as well to quads, borders, slugs, brass rule, furniture, etc., whether made of metal, wood, plastic or other materials.

In the drawing:

Fig. 1 is a plan view of two lines of type made in accordance with this invention;

Fig. 2 a transverse vertical sectional view on the line 2—2 of Fig. 1;

Fig. 3 is a transverse vertical sectional view, similar to Fig. 2, showing the head of the type slightly reduced;

Fig. 4 side elevations of a type and a space piece;

Fig. 5 a perspective view of the lead;

Fig. 6 a plan view of two lines of set type, the leads being of such thickness as to form spacing means for the lines of type;

Fig. 7 a transverse vertical, sectional view on the line 7—7 of Fig. 6;

Fig. 8 a transverse vertical sectional view of two lines of type spaced apart by an extra lead;

Fig. 9 a transverse vertical, sectional view of two lines of type showing a slightly modified form of lead; and

Fig. 10 a detail view of a slightly modified form of space piece.

Referring to the various parts by reference characters, 1 designates a single type. At its front the type is cast to form the shallow recess 2 extending from the bottom or foot of the type to a point slightly below the head or top of the type. The upper wall of this recess is formed by a forwardly projecting short shoulder 3, said shoulder forming the lower side of a forwardly projecting head portion 3^a. The head of the type, containing the printing face, is of full point size, while the body of the type from the shoulder 3 to the foot of the type is reduced by the depth of the recess 2. In that portion of the front face of the type which forms the long wall of the recess a transverse groove 4 is formed approximately midway between the shoulder 3 and the foot or bottom of the type. This groove extends entirely across the front of the type.

The recess 2 is so shallow and the forwardly extending head 3^a is so short that the weight of the overhanging head portion will be a very small fraction of the whole weight of the type. The said head portion will be mainly outside of the vertical plane of the impression surface of the printing character on the type face as clearly shown in Figs. 2, 3, 7, 8 and 9, and will be substantially unaffected by the downward compression stress of the printing operation. Because of the slight reduction in the cross sectional area of the body of the type the type will be self-sustaining in set position thereby permitting individual setting of type in a line. The head portion 3^a serves as a means to indicate the proper setting position of the type and there is no danger of inverted letters being set.

The space pieces 5 are equal in point size to the body of the type below the shoulders 3 and are slightly shorter than the recess 2 so that their upper ends, when set in a line of type, will be at the same level as the upper edge of the lead. Each space piece is formed with a transverse groove 6 in its front face corresponding in shape with the groove 4 in the type. This groove 6 is midway between the upper and lower ends of the space piece and will register with the corresponding grooves in the type when set in a line, and the front surface of the space piece 50 will be flush with that portion of the front surface of the type which forms the long wall of the recess 2.

The assembled line of type and spaces are locked together by a lead 7 which is adapted to fit in the recess 2. The lead is equal in thickness

ness to the depth of the recess 2, so that when in position its front surface will be flush with the front surface of the head 3^a of the type above the shoulder 3, and it is of such width as to extend from a point close to the shoulder 3 to the bottom or foot of the type. The front face of the lead is formed with a longitudinally extending groove 8, and its rear face which contacts with the long wall of the recess 2 is formed with a longitudinally extending rib 8^a, the groove and rib being located midway between the upper and lower edges of the lead. The rib 8^a is adapted to fit in the grooves 4 of the type and the grooves 6 of the spaces when the type and spaces are assembled in a line, and lock them to the lead against material independent upward or downward movement relative to each other and to the lead. There might be a slight vertical relative movement of the type and lead due to the slight clearance between the rib of the lead and the upper and lower ends of the grooves in the type and spaces. A slight clearance is provided between the shoulder 3 and the upper edge of the lead to facilitate the insertion and removal of the lead. The rib 8^a is smaller than the grooves 4 in the type and grooves 6 in the spaces to facilitate the insertion of the lead.

As shown in Fig. 2, the lead fills the recess 2 in the type except for the slight clearance under shoulder 3. The front face of the lead is without projections, and is flush with the front face of the forwardly projecting head portion 3^a so that when assembled in a line, the type and the lead occupy the same transverse area in the line as a standard type of the same point size would occupy. This permits the lines of type to be set solid while interlocked with the leads. The rear sides of the type and spaces are smooth and the forward face of the lead in which is formed groove 8, bears against the smooth rear face of the next line of type when the lines are set solid, so that an entire interlocked line, together with the interlocked lead, may be readily removed as a unit from the stick, galley, or chase, for purposes of correction or change and with less danger of pying.

The type may be set directly against the lead, and because of the recess 2 which receives the lead all danger of inverted letters is avoided. The groove 8 and the rib 8^a are located midway between the upper and lower edges of the lead so that it may be used with either edge up under shoulder 3. This simplifies the handling of the leads. The grooves 6 are formed in the spaces midway between the upper and lower ends thereof so that they may be used with either end up. This has obvious advantages.

Fig. 3 shows a type with a head portion reduced in point size and cast on a smaller body than it was originally designed for. The extent of the reduction of the head portion is determined by the design of the type face, depth of the descenders, etc. In this figure the lead and the body portion below the head portion indicate the original size. The reduction in point size makes the type flexible, enabling one to set the lines closer if necessary by merely reducing the thickness of the lead.

In Figs. 6 and 7 the leads are shown of sufficient thickness to serve as means for spacing the set lines of type.

In Fig. 8 the lines of set type are spaced apart by inserting an extra lead, the rib 8^a of the extra lead fitting the groove 8 of the adjacent contacting lead.

In Fig. 9 the leads are shown with a rib on one face the opposite face being smooth and without the groove 8. This form of lead is desirable in certain applications of the invention.

5 The spaces 5 may be formed with grooves 6 in their opposite faces as shown in Fig. 10, in order that either face may be placed in contact with the lead.

10 The term "front" used in the foregoing specification and in the succeeding claims is to be construed as designating that portion of the type which is uppermost when the type is placed or seated in the holder or "stick" in which it is set for printing, as shown in Figs. 1 and 6 of the 15 drawing.

10 While I have illustrated and described the preferred form of construction for carrying my invention into effect this is capable of variation and modification, without departing from the 20 spirit of the invention. I, therefore, do not wish to be limited to the precise details of construction set forth, but desire to avail myself of such variations and modifications as come within the scope of the appended claims.

25 What I claim is:

1. The combination of a printing type formed with a solid body rectangular in transverse section at all points in its height, recessed on its front surface to form a short forwardly extending head portion which bears the type face and constitutes the printing surface, said recess being so shallow that the weight of the over-hanging head portion will be a very small fraction of the whole weight of the type, and will be unaffected by the downward compression stress of the printing operation and the type will be self-sustaining in set position to permit individual setting of type in a line, and a thin lead fitting within said recess with its front surface substantially flush with the front surface of the forwardly projecting head portion of the type to permit the lines of type to be set "solid" with the leads enclosed within and between the lines.

35 2. The combination of a printing type recessed on its front surface to form a short forwardly extending head portion which bears the type face and constitutes the printing surface, said recess being so shallow that the said head portion will be mainly outside of the vertical plane of the impression surface of the printing character on the type face and the weight of the over-hanging head portion will be a very small fraction of the whole weight of the type, and will be substantially unaffected by the downward compression stress of the printing operation and the type will be self-sustaining in set position to permit individual setting of type in a line, and a lead fitting within said recess with one face contacting the vertical wall of said recess and its front surface in a vertical plane parallel with the vertical front surface of the forwardly projecting head portion of the type.

40 3. The combination of a printing type formed with a solid body rectangular in transverse section at all points in its height recessed on its front surface to form a slight forwardly extending head portion which bears the type face and constitutes the printing surface, said recess extending from said head portion to the foot or bottom of the type, the rear surface of said type being smooth, said recess being so shallow that the weight of the over-hanging head portion will be a very small fraction of the whole weight of the type, and will be substantially unaffected by the downward compression stress of the printing

operation and the type will be self-sustaining in set position to permit individual setting of type in a line, a groove being formed across the surface of the type in the wall of the said recess approximately midway between the said head portion and the bottom of the type, a lead fitting within said recess and extending from a point close to the underside of said head portion to the bottom of the type with one face contacting the vertical wall of said recess and its front surface in a vertical plane parallel with the vertical front surface of the forwardly projecting head portion of the type, and a rib on the lead adapted to fit within the said groove in the type body to interlock the type to the lead.

4. The combination of a printing type recessed on its front surface to form a slight forwardly extending head portion which bears the type face and constitutes the printing surface, said recess being so shallow that the weight of the over-hanging head portion will be a very small fraction of the whole weight of the type, and will be mainly outside of the downward compression stress of the printing operation and the type will be self-sustaining in set position to permit individual setting of type in a line, a lead fitting within said recess with one face contacting the vertical wall of said recess and its front surface in a vertical plane parallel with the vertical front surface of the forwardly projecting head portion of the type, and means to lock the lead to the type against separation by a relative up and down movement between the type and the lead.

5. The combination of a printing type formed with a solid body smooth on its rear surface and rectangular in transverse section at all points in its height and recessed on its front surface to form a short forwardly extending head portion which bears the type face and constitutes the printing surface, said recess being so shallow that the weight of the over-hanging head portion will be a very small fraction of the whole weight of the type, and will be unaffected by the compression stress of the printing operation and the type will be self-sustaining in set position to permit individual setting of type in a line, a thin lead fitting within said recess with one face contacting the vertical wall of said recess and its front surface substantially flush with the front surface of the forwardly projecting head portion of the type to permit the lines of type to be set "solid" with the leads enclosed within and between the lines, a space piece equal in

thickness from front to rear to the recessed portion of the body of the type, and means to lock the lead to the type and the space piece against separation by a relative up and down movement between the type, the space piece and the lead.

6. The combination of a printing type formed with a solid body rectangular in transverse section at all points in its height with a smooth rear surface and recessed on its front surface 10 to form a slight forwardly extending head portion which bears the type face and constitutes the printing surface, said recess extending from said head portion to the foot or bottom of the type and being so shallow that the weight of 15 the over-hanging head portion will be a very small fraction of the whole weight of the type, and will be substantially unaffected by the downward compression stress of the printing operation and the type will be self-sustaining in set 20 position to permit individual setting of type in a line, a groove being formed across the surface of the type in the wall of the said recess approximately midway between the said head portion and the bottom of the type, a lead fitting within 25 said recess and extending from a point close to the underside of said head portion to the bottom of the type with one face contacting the vertical wall of said recess and its front surface in a vertical plane parallel with the vertical front surface of the forwardly projecting head portion of the type, a space piece equal in thickness from front to rear to the recessed portion of the body of the type and formed with a groove across 30 its front surface, and a rib on the lead adapted to fit within the said grooves in the type body and space 35 piece to interlock the type and space piece to the lead.

7. A printing type recessed on its front surface only to form a slight forwardly extending head portion which bears the type face and constitutes the printing surface, said recess extending to the bottom of the type and the front wall of the type within said recess being formed with a transverse groove and said recess being so shallow that the weight of the over-hanging head portion will be a very small fraction of the whole weight of the type, and will be substantially unaffected by the downward compression stress of the printing operation, and the type will be self-sustaining in set position to permit individual setting of type in a line, said recess and said 45 groove being adapted to receive an interlocking lead.

SOLOMON SIEGELBAUM.
